UNITED STATES PATENT OFFICE.

FRANCIS L. O'BRYAN, OF WINSTON-SALEM, NORTH CAROLINA, ASSIGNOR
OF ONE-HALF TO WILLIAM T. BROWN, OF WINSTON-SALEM, NORTH
CAROLINA.

ELECTRICAL DISPLAY SYSTEM.

SPECIFICATION forming part of Letters Patent No. 743,024, dated November 3, 1903.

Application filed December 20, 1902. Serial No. 136,067. (No model.)

To all whom it may concern:

Be it known that I, FRANCIS L. O'BRYAN, a citizen of the United States, residing at Winston-Salem, in the county of Forsyth and State 5 of North Carolina, have invented certain new and useful Improvements in Electrical Display Systems, of which the following is a specification.

My invention relates to that class of electrical display systems in which electric lamps are arranged in the form of letters or are arranged to illuminate letters in transparent compartments which are so arranged as to form a word, combination of words, or a sign. 10 In such systems the separate lamps composing the several letters or illuminating the several letters have heretofore been so connected with the source of electricity that the letters may be successively formed or brought 15 into view or they may be simultaneously exposed. The lamps have also been so arranged that different letters may be formed by causing different lamps in the same group or block to glow at different times.

20 The object of my invention is to improve electrical display systems of this class and to provide means whereby a series of letters may be brought into view in any desired way and whereby sparking and burning of parts of the 25 apparatus may be avoided while changing the several circuits.

Other features of my invention will be more clearly hereinafter set forth.

In the accompanying drawings, Figure 1 is 30 a plan view of the apparatus which I employ for controlling and directing the circuits of the system. Fig. 2 shows a side elevation thereof. Fig. 3 is a detail view in elevation of the main switch for opening and closing 35 the main circuit. Fig. 4 is a detail view in elevation of the devices for successively closing the circuits leading to different groups of lamps. Fig. 5 is a detail view in section of 40 part of the devices for directing the currents through the circuit-changing wheel which I employ. Fig. 6 is a detail view in elevation of the devices employed for changing the circuit through different lamps in the same group or block. Fig. 7 is a diagram illustrating how 45 my apparatus operates in connection with

groups of electric lamps to form letters or combinations of letters in the desired order. In this figure I have illustrated "monograms" or an arrangement of lamps by which a plurality of letters may be formed 55 from the same bank of lamps. Fig. 8 is a diagram illustrating the operation of my apparatus in which monograms are omitted, but in which three circuits are used for the purpose of illuminating a series of lamps of different colors. Fig. 9 is a detail view showing how transparent signs may be employed in front of electric lamps in separate compartments. The devices shown in Fig. 9 may be used in connection with the circuits shown in 60 Fig. 8. Fig. 10 is a diagram illustrating the manner in which the circuits may be arranged and when the letters of a word are displayed in always the same order, differing from Fig. 8, which latter figure shows devices for changing 65 the order in which the letters may be displayed.

The apparatus shown in Figs. 1 and 2 for controlling the circuits may be located at any desired distance from the electric lamps which 70 compose or which illumine the letters, signs, or designs. The several parts of the circuit-controlling mechanism are preferably all located on a common base-plate A. The two branches B C of the main-line circuit from a 75 generator are connected with a fuse-block D of ordinary construction, and from this fuse-block extend conductors b and c, connected, respectively, by way of the fuse with the conductors B and C. The conductor c is electrically connected with a spring contact-finger E, which bears on a sleeve e, that is mounted to turn on a shaft e', supported on standards rising from the bed-plate. The sleeve is insulated from the shaft and carries three radial arms F F' F'', arranged at an angle of 80 about one hundred and twenty degrees with each other and adapted to successively make electrical connection with the three bifurcated contact-springs G G' G'', which are insulated from each other and each of which is connected with one of the conductors H H' 85 H''. The arms F F' F'' are all electrically connected with the sleeve e, and when one of the arms makes electrical connection with one of 90

the springs G G' G^2 the current will pass through the conductor H , H' , or H^2 connected with such spring. Only one arm F , F' , or F^2 can make electrical connection with a spring 5 G G' G^2 at any one time.

The branch B of the main circuit is extended at b , as before stated, and this conductor b is electrically connected with the contact device i , forming part of the main 10 switch I , and attached to a base i' , of insulating material. Another contact device i^2 on the base i' is connected with a wire J , that leads to the devices for controlling the circuits leading to the lamps. i^3 i^4 indicate two 15 other contact devices on the base i' . They are insulated from the contacts i i^2 , but are connected to each other by a piece of good conducting material i^5 . It is obvious that if the contacts i and i^2 are electrically connected 20 with each other and the contacts i^2 and i^4 are simultaneously connected in like manner a current of electricity may pass from conductor B through the switch I to the conductor J . For doing this I employ two spring or 25 yielding contact devices I' I^2 , carried by a vertical oscillating frame K , which has an arm k , attached to a shaft k' , mounted in bearings in lugs k^2 , rising from the base of the switch. Springs k^4 , wound around the shaft 30 attached thereto and bearing on the base i' , tend to raise the frame in such manner as to withdraw the contacts I' I^2 from the contacts i i^2 i^3 i^4 . On its upper side the arm k is formed with two lugs k^5 k^6 and an inclined surface k^7 35 between the lugs, on which bears the downwardly-extending arm l of a bell-crank lever L , pivoted above the arm k to standards l' and having a laterally-projecting arm l^2 , to which is attached an upwardly-projecting rod 40 l^3 , carrying an eye l^4 , through which extends a pitman-rod M , provided with two stops or bumpers m m' , placed some distance apart and rigidly attached to the rod. The bumper m' is attached to one end of the rod M , and 45 the opposite end of the rod is jointed to a wrist-pin m^2 on a crank-arm M' , attached to a horizontal shaft M^2 , mounted in bearings in standards M^3 and carrying a worm-wheel M^4 , gearing with a worm M^5 , the shaft of which 50 carries a worm-wheel M^6 , gearing with a worm M^7 on a shaft M^8 , to which the driving-pulley M^9 is secured. To the wrist-pin m^2 is also jointed one end of a rod N , the opposite end of which is connected with a pawl-carrying 55 lever n , attached to a sleeve n' , which is adapted to rock about the axis of the shaft e' . A block n^2 of insulating material is interposed in the connection between the rod N and the lever n , so that current may be prevented from passing from the sleeve e to the 60 rod.

The pawl n^3 engages a ratchet-wheel N' , rigidly connected with the sleeve e , having three teeth or notches n^4 , arranged an equal distance apart. As the crank-arm M' is revolved 65 the pawl-carrying lever n is moved back and

forth. On its inward movement it engages one of the teeth n^4 and imparts one-third of a revolution to the ratchet-wheel N' , and thus causes one of the arms F , F' , or F^2 to be withdrawn from the spring-contacts G G' G^2 and another arm to be brought into engagement with one of such spring-contacts. The purpose of this operation will be herein-after described.

In Fig. 2 the switch I is shown as closed. At this time the arm l is arranged vertically and holds down the switch, and the parts will remain in this position until the crank-arm has revolved nearly one-half of a revolution 80 and the stop or bumper m abuts against the rod l^3 and causes the arm l to be turned slightly from its vertical position, at which time the springs k^4 will cause the frame K to be raised suddenly, thus breaking the electrical connection at the contacts i , &c. Soon after this the pawl engages one of the teeth n^4 , this being at the time when the wrist-pin m^2 is about at the limit of its movement to the right. As soon as the wrist-pin begins to move back the pawl n^3 will be moved in such manner as to turn the ratchet-wheel N' , and thus turn the sleeve e , carrying the arms F F' F^2 . While the ratchet is thus being turned, the switch I remains up or open, and the current is broken. The switch is not again closed until the stop or bumper m' has been moved into engagement with the rod l^3 —i.e., until the wrist-pin m^2 has moved to the opposite side of the shaft M^2 —and by this time 95 the arms F F' F^2 have had their positions changed. It will thus be seen that the positions of the arms F F' F^2 are changed while the current is open at the switch I , and thus 100 sparking between the parts F F' F^2 and G G' G^2 is avoided.

The gearing between the driving-pulley and the crank-arm M' is a slow one, so that the switch I is open or closed for some considerable time at each revolution of the driving-shaft.

A short crank-arm O , attached to the opposite end of the shaft M^2 , is connected by means of a rod o with an arm o' , projecting upwardly from a circuit-closing bar P , which 115 is pivoted to a post o^2 , attached to a plate P' , of insulating material. This post is electrically connected with the wire J and also with the bar P .

Q Q^2 Q^3 Q^4 Q^5 Q^6 indicate a series of spring-contacts attached to the plate P' and insulated from each other. They are adapted to successively make electrical connection with the bar P . It will be observed that the contacts Q Q^2 , &c., gradually decrease in length 125 or height from that one nearest the post o^2 outward. As the bar P moves downward it first makes electrical connection with the contact Q and then successively with the other contacts Q^2 , &c. Each of the contacts Q Q^2 , &c., is connected with a separate wire q q^2 q^3 q^4 q^5 q^6 , and these wires are sepa-

rately connected with contact-fingers $r' r^2 r^3 r^4 r^5 r^6$, carried by a bar R, of insulating material, which also carries contact-fingers $s' s^2 s^3 s^4 s^5 s^6$, each of which is connected with a separate wire $t' t^2 t^3 t^4 t^5 t^6$, which lead out to the electric lamps forming or illuminating the letters, signs, or designs.

It is obvious that if the current of electricity passes through the wire J to the bar P while the latter is descending it will be subdivided and successively pass through the wires $q' q^2, \&c.$, and if the fingers $r' r^2, \&c.$, be electrically connected with the fingers $s' s^2, \&c.$, in the order stated currents of electricity will be successively sent into the wires $t' t^2, \&c.$

In order to pass the currents from the fingers $r' r^2, \&c.$, to the fingers $s' s^2, \&c.$, I employ a wheel U, of insulating material, to which are secured a series of radial rows of contacts. Each radial row comprises six contact-plates $u' u^2 u^3 u^4 u^5 u^6$. The wheel is mounted to revolve in a supporting-frame W in such manner that the contact-plates will be brought into electrical connection with the fingers r' and s' , &c. The contact-plates $u', \&c.$, in one radial series are connected with the contact-plates $u', \&c.$, in the diametrically opposite series by wires $v' v^2 v^3 v^4 v^5 v^6$. By suitably wiring the wheel I may cause the currents to be sent into the circuit-wires $t' t^2, \&c.$, in any desired order. For instance, if it is desired to display the word "Patent" at the lamps the word may be spelled out in the order "P-A-T-E-N-T," in which case the plate u' on one side of the wheel would be connected with the plate u' on the diametrically opposite side, and the remaining contact-plates would be connected in regular order in the same way; but for advertising and other purposes it is sometimes found desirable to mix the letters, so that the letters will not appear in regular order, to display a word, this method being found to more effectively attract attention. Thus in Fig. 7 the contact u' on one side of the wheel is shown as being connected with the contact u' on the other side thereof, the contact u^2 with the contact u^4 , the contact u^3 with the contact u^5 , the contact u^4 with the contact u^6 , the contact u^5 with the contact u^3 , and the contact u^6 with the contact u^4 , so that the letters of the word "Patent" would appear in the following order: "P-E-A-N-T-T;" but as these letters are properly arranged at the sign they will of course appear in proper relative positions and will spell the word correctly when the letters have all been brought into view. By changing the wiring the letters may be made to appear in any other desired way. In Fig. 7 I have shown two other radial series of contact-plates $u', \&c.$, connected in a different way. When these two series are in contact with the fingers $r', \&c.$, $s', \&c.$, the word "Patent" will be spelled in the following order: "T-N-P-T-E-A;" but at the lamps while these letters are brought into view in

the order stated they appear in proper regular order when the entire word is displayed. This method of operation naturally arrests the attention of the observer and increases his interest in the operation of the apparatus and causes him to linger to observe or hear whatever else may be going on in the immediate vicinity.

The wheel U is provided with a series of radial pins or teeth w , which are adapted to engage with an arm or wiper w' on the shaft M^2 . This shaft revolves slowly and moves the wheel a short distance once in each of its revolutions—that is to say, the wheel is moved or advanced only once during each revolution of the shaft M^2 , and therefore only once between the times occupied in completely making and breaking the circuits by the bar P. In this way sufficient time is given to spell out a word and expose it to view. In Fig. 2 I have shown the wheel U provided with eight radial series of contacts $u', \&c.$, on one side and eight radial series of contacts $u', \&c.$, on its opposite side, so that the wheel is adapted to cause eight different arrangements of the letters in the words to be displayed during one revolution—i. e., to display the same word with the letters appearing in different order or to display a number of different designs or the same designs in different orders. Referring now to Fig. 7, c indicates the conductor leading from the main-line conductor C, as before explained, and in this diagram E indicates the contact-finger that is represented in Figs. 1 and 2 as bearing on the sleeve e, but in this diagram it is shown as adapted to make contact with points $x x' x^2$ at the ends of the conductors $H H' H^2$ corresponding with the conductors similarly located in Figs. 1 and 2. These conductors $H H' H^2$ may be of any desired length and lead to the letters or signs.

It has heretofore been proposed to employ blocks of lamps from which two or more letters may be formed by suitable wiring. Such blocks of letters are commonly called "monograms." If it is desired to produce only one letter from the block of lamps, only one circuit-wire H , H' , or H^2 would be necessary, but when it is desired to produce, say, three letters from the same block it is necessary or usual to use three wires $H H' H^2$. The wire H^2 is shown in Fig. 7 as being so connected with the lamps in the first block by wires y as to cause the lamps so connected to display the letter "S" when they receive current from the wire H^2 . The wire H' is in like manner connected with the lamps in the first block by wires z in such manner that the lamps so connected will display the letter "L," and the wire H is connected with lamps in the first block by wires z' in such manner as to cause the letter "D" to be displayed. The wire H^2 is disconnected with the lamps in the second block by wires y' in such manner as to display the letter "L," and the wire H' is connected by wires z^2 in such manner as to display the letter

"I." The wire H is connected at z^3 in such manner that the letter "L" may also be under the control of the wire H . Any desired number of blocks of lamps may be used and each 5 block may be arranged to produce any desired number of letters by following out the same system of wiring.

A single return-wire $t' t^2 t^3 t^4 t^5 t^6$ is connected to each block of lamps and leads to the 10 circuit-controlling apparatus, being connected to the fingers $s' s^2$, &c., in the manner before described.

In Figs. 8 and 9 I have shown diagrammatically a system in which no provision is made 15 for forming letters by the lamps; but the system is suitable for illuminating letters formed on glass or other such transparent material. In Fig. 9 I have shown a series of compartments, each containing three lamps, which may 20 be of different colors. Each compartment has a transparent letter displayed at the front, and each compartment is separated from the others. The switch E in Fig. 8 controls the lamps of different colors. Thus all the lamps connected with the wire H may be red, those connected with H' blue, and those connected with H^2 green. In this way a word may be first 25 displayed in red letters, then in blue, and then in green. I have also shown in Fig. 8 the 30 system as adapted to display the letters in any desired order. Of course the colors of the lamps may be varied or the lamps in one compartment may be of a different color from those contained in the same circuit in any 35 other compartment.

In Fig. 10 I have shown a system similar to that shown in Fig. 8, except that the devices for displaying the letters of a word in irregular order are omitted.

40 I have described the system as being adapted to display letters; but of course I may use the same system for displaying words, characters, designs, pictures, or any other desired object or objects.

45 Referring now to the apparatus shown in Figs. 1 and 2 for controlling the circuits, it will be remembered that the current from the generator comes in at C and passes through the conductors $H H' H^2$. The current returns 50 by the wires $t' t^2$, &c., passes to the contacts $Q' Q^2$, &c., then to the bar P , then to the conductor J and the switch I , conductor b , and then to the main-line wire B . In Figs. 1 and 2 the apparatus is in the position where the 55 circuit is broken at P ; but the switch I is closed, the arm l being vertical and the crank-arm M' nearly at the end of its outward movement to the left. The bumper m' is, however, in contact with the eye l^4 . The arm F' is in contact with the spring-finger G^2 . As the driving-shaft revolves the shaft M^2 is revolved slowly, and the crank-arm O causes the bar P to be depressed, closing the circuits slowly through the contacts Q' , &c., and thus spelling 60 out the word, the wheel U at this time being stationary. As the bar P is being de-

pressed the rods M and N are moved inward, the pawl n^3 being pushed back to engage a new tooth in the ratchet-wheel; but the switch I is not interfered with at this time, and the 70 circuit remains closed. The bar P engages all the contacts $Q' Q^2$, &c., when the crank-arm O has reached its dead-center, and thereafter the bar P remains in electrical connection with the contacts Q' , &c., for some time, 75 thus displaying the complete word for a length of time sufficient to be distinctly seen. After this the bumper m comes against the eye l^4 and causes the arm l to be moved out of its vertical position, and then the springs h^4 act to 80 very quickly open the switch, and thus break the circuit. Soon after this the pawl n^4 engages a tooth of the ratchet, and the arm w engages one of the pins w' . As the arm w moves upward it causes the wheel U to be turned, 85 so as to move two diametrically opposite radial series of contacts $u' u^2$, &c., out of engagement with the fingers $r' s'$, &c., and at the same time the bar P is slowly lifted, and the ratchet is turned to cause the arm I^2 to 90 break contact at G^2 and the arm F' to make contact at G' . Further movement of the wheel U causes two new diametrically opposite series of contact-plates to be brought into electrical connection with the contact-fingers 95 $r' s'$, &c. While the bar P , wheel U , and ratchet N' are being thus moved the circuit is open at the main switch I , and thus I avoid 100 sparking when making and breaking the circuits. After the fingers $F F' F^2$ have been 105 thus shifted, the bar P lifted, and wheel U advanced the bumper m' comes against the rod b^3 and moves the frame K down, causing the circuit to be closed at the switch I . While 110 the circuit is broken at the bar P , the switch I is closed slowly, the arm l moving slowly over the surface k^7 until it reaches a vertical position, at which time the switch I will be 115 completely closed. When this occurs, the parts will appear in the position shown in 120 Figs. 1 and 2, and then the bar P will begin to descend, and the other mechanism will be 125 successively operated in the order and in the manner before described.

I have described the best way now known 115 to me of carrying out my invention; but I do not wish to confine myself to the precise details of construction shown and described or to the exact organizations and combinations set forth. Some of my improvements may 120 be used independently of the others or in apparatus or systems of different kinds from that herein described.

The provision which I make for opening and closing the circuits when the main switch 125 is open is a most desirable one, and the devices which I employ for successively displaying the letters of the word in any desired order render the system most attractive and useful for advertising and other purposes. 130

I claim as my invention—

1. In an electrical display system, the com-

bination with electric lamps, a main line, a plurality of branch wires leading from the main line to the lamps, a larger number of return-wires leading from the lamps back to the main line, and means for causing the current to pass successively and automatically from the main line through the branch wires.

2. In an electrical display system, the combination of a plurality of blocks of electric lamps, a main line, a plurality of branch wires leading from the main line to the blocks of lamps, a larger number of return-wires leading from the lamps back to the main line, and means for causing the current to pass successively and automatically from the main line through the branch wires and back to the main line through the return-wires.

3. In an electrical display system, the combination of a series of blocks of electric lamps with the lamps in each block arranged and wired to form a monogram, a main line, a plurality of branch wires leading from the main line, and each connected with one of the groups of lamps in one or more of the blocks, return-wires one for each block of lamps, and means for causing the current to pass successively and automatically through the branch wires.

4. In an electrical display system, the combination of a series of blocks of electric lamps with the lamps in each block arranged and wired to form a monogram, a main line, a plurality of branch wires leading from the main line, and each connected with one of the groups of lamps in one or more of the blocks, a return-wire leading from each block of lamps to the main line, means for automatically shifting the current from one outgoing branch wire to another, and devices for successively and automatically connecting the return-wires with the main line.

5. In an electrical display system, the combination of a series of blocks of electric lamps, a main line connected therewith, a separate return-wire connecting each block of lamps with the main line, means for successively closing the circuit of each block of lamps, and devices for controlling the order in which said circuits are closed.

50 6. In an electrical display system, the combination of a series of blocks of electric lamps, a main line connected therewith, a separate return-wire connecting the main line with each block of lamps, means for successively and automatically closing the circuit of each block of lamps, and means for automatically changing the order in which said circuits are closed.

60 7. In an electrical display system, the combination of electric lamps, a main line, a plurality of branch wires connecting the main line with the lamps, a larger number of return-wires connecting the lamps with the main line, means for automatically and successively causing the current to pass through the branch wires; means for automatically

opening and closing the main line at regular intervals, means for opening the return-circuits while the main line is open, and means for opening one of the branch circuits and closing another when the main line is open.

8. In an electrical display system, the combination with electric lamps of a main line, a plurality of circuits connecting the main line with the lamps, means for opening and closing the main line at intervals, means for successively closing the return-circuits, and for controlling the order in which they are opened and devices for shifting the controlling means while the main line is open.

9. The combination of a main line, a switch for automatically opening and closing the main line at regular intervals, a plurality of branch wires, means for automatically shifting the current from one branch wire to another, a plurality of return-wires, means for successively connecting them to the main line while the main line is closed, and means for changing the order in which the return-circuits are closed.

10. The combination of a main line, a switch connected therewith, a plurality of branch wires, contacts with which they are connected, a plurality of rotary arms adapted to engage said contacts, electric lamps included in the circuits of the branch wires, return-wires from the lamps connected with the main line, a rotating shaft, connections between the shaft and the switch of the main line for opening and closing it, and connections between the shaft and the rotary arms.

11. The combination of a main line, a switch connected therewith, a plurality of branch wires, a switch for alternately connecting said wires with the main line, electric lamps included in the circuits of the branch wires, a plurality of return-wires from the lamps, a switch for successively connecting the return-wires with the main line, a shifting contact-carrying wheel for controlling the order in which the circuits are closed through the return-wires, a rotary shaft, and connections between said shaft and the switch for opening and closing the main line, the switch for opening and closing the branch circuits, the switch for opening and closing the return-circuits, and for operating the wheel which controls the order in which the return-circuits are opened and closed.

12. In an electrical display system the combination with groups of lamps and their circuit connections, of a wheel moved step by step and having means for changing the circuits whereby the order in which the circuits are closed through the lamps may be changed.

13. In an electrical display system the combination of a disk or wheel provided with radial series of contacts, connections between the contacts in one radial series with the contacts in the diametrically opposite series, contact-fingers engaging the contacts of the wheel on opposite sides thereof, groups of

electric lamps, a main line, connections between the lamps and the main line, return-wires from the lamps connected with one set of contact-fingers, a switch to which the other 5 set of contact-fingers are connected, and connections between this switch and the main line.

In testimony whereof I have hereunto subscribed my name.

FRANCIS L. O'BRYAN.
